(57) **CLAIM**

The ornamental design for a 3D printer enclosure, as shown and described.

DESCRIPTION

FIG. 1 is a top perspective view of a first embodiment of the design for the 3D printer enclosure;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a bottom view thereof; and

FIG. 8 is a top view thereof.

FIG. 9 is a top perspective view of a second embodiment of the design for the 3D printer enclosure;

FIG. 10 is a bottom perspective view thereof;

FIG. 11 is a front view thereof;

FIG. 12 is a back view thereof;

FIG. 13 is a left side view thereof;

FIG. 14 is a right side view thereof;

FIG. 15 is a bottom view thereof; and,

FIG. 16 is a top view thereof.

The portions shown in broken lines are for illustrative purposes only and form no part of the claimed design.

The portions shown with a hatching pattern in FIGS. 1-16 are of a same material and/or a same color. The differences in the hatching patterns are for illustrative purposes to show the different portions of the 3D printer enclosure.
